CLAIM

The ornamental design for a shower caddy, as shown and described.

DESCRIPTION

FIG. 1 is a front-left perspective view of a shower caddy of the claimed design;

FIG. 2 is a front view of the shower caddy of FIG. 1;

FIG. 3 is a rear view of the shower caddy of FIG. 1;

FIG. 4 is a left side view of the shower caddy of FIG. 1;

FIG. 5 is a right side view of the shower caddy of FIG. 1;

FIG. 6 is a top view of the shower caddy of FIG. 1; and,

FIG. 7 is a bottom view of the shower caddy of FIG. 1.

The broken lines shown in the figures represent portions of the shower caddy that form no part of the claimed design.
